CLAIM

The ornamental design for exterior fingertip protectors for a glove, as shown and described.

DESCRIPTION

FIG. 1 is a palmar view of the exterior fingertip protectors for a glove in an operable position on a glove thereof; FIG. 2 is a right elevational side view thereof; FIG. 3 is a dorsal view thereof; FIG. 4 is a left elevational side view thereof; FIG. 5 is a top view thereof; and, FIG. 6 is a bottom view thereof.

The broken line showing of the glove in all views is for illustrative purposes only and forms no part of the claimed design.
